HAIR AND SCALP TREATMENT CABINET

William D. Nolan, Wichita Falls, Tex.

Application April 4, 1955, Serial No. 35,344

Term of patent 14 years

(Cl. D4—2)

Fig. 1

Fig. 3

Fig. 2

Fig. 1 is a perspective view of a hair and scalp treatment cabinet embodying my new design;

Fig. 2 is a front elevational view; and

Fig. 3 is a side elevational view thereof, showing the side not shown in Fig. 1 and with the cover portion in raised position.

The rear and bottom of the cabinet are substantially plain.

The dominant feature of my design resides in the full line portion of the drawing.

I claim:

The ornamental design for a hair and scalp treatment cabinet, as shown and described.
